CLAIM

I claim the ornamental design for the fluid connector, as shown and described.

DESCRIPTION

FIG. 1 is a first perspective view taken from a first end of a fluid connector showing my new design;

FIG. 2 is a second perspective view taken from a second end thereof;

FIG. 3 is a front elevational view thereof;

FIG. 4 is a top view thereof;

FIG. 5 is a bottom view thereof;

FIG. 6 is a left end view thereof;

FIG. 7 is a right end view thereof; and,

FIG. 8 is a rear view thereof.
